PORTABLE ELECTRIC LANTERN

Charles S. Packer, Chicago, Ill., assignor to Just-
rite Manufacturing Company, Chicago, Ill., a
corporation of Illinois

Application January 22, 1940, Serial No. 314,975

19 Claims. (Cl. 240—10.63)

The present invention relates to portable electric lanterns, and more in particular to such lanterns particularly adapted for railway signaling and the like.

Among the objects of the present invention is to provide a portable electric lantern particularly adapted for railway signaling and the like, having a plurality of lamps which may be selectively positioned for operation substantially centrally with respect to the lantern.

A still further object of the present invention is to provide a novel portable lantern including a novel arrangement of elements whereby any one of a plurality of lamps may be readily and easily positioned substantially centrally with respect to a reflector by the manual manipulation of a switch adapted to selectively establish electrical circuits including any one of said lamps.

More particularly, the present invention has an object the provision of a novel switch disposed within the said circuit which serves as a mounting for one or more lamps associated with a reflector.

The present invention also comprehends a novel mounting for the said switch whereby operation thereof is facilitated and wherein means which is provided for the operation thereof is constituted by a switch element manually operable exteriorly of the said housing and cooperating with said switch at all times.

Still a further object of the present invention is to provide novel means for holding said switch against displacement in any of a plurality of positions.

The present invention also includes as an object the idea of providing means associated with the said switch element whereby the said switch element is selectively controlled.

As a further object of the present invention, novel means is provided to completely insulate a battery set or the like from the housing to prevent the completion of an electrical circuit therewith irrespective of the position of the battery set within the housing. Inasmuch as the invention embraces means at the reflector head for normally interrupting this circuit, the present improvement includes novel means used in conjunction with such structure and in opposition thereto which will insulate the said battery should the same be placed within the housing in a position reverse from its normal operative position with respect to the said reflector head.

As a further object of the present invention, novel means is incorporated in the portable lan-

tern to provide a support therefor whereby the portable electric lantern is pivotally mounted thereon for varying the angularity of the projected beam of light as desired. More particularly, this improved structure may be embodied in the form of a support providing an additional lamp guard projecting outwardly from the lamp housing and which is so constructed and arranged with respect to the lamp guard as to normally provide clearance whereby said lamp guard has unobstructed movement at all times during angular movement of the lantern with respect to said support. In addition, such pivotal connection between the support and the housing may also serve as a pivotal mounting for a handle used for carrying the lantern from place to place.

Other objects, features, capabilities and advantages are comprehended by the invention, as will later appear and as are inherently possessed thereby.

Referring to the drawings:

Figure 1 is a view in perspective of a portable lantern embodying a modified construction within the scope of the present invention;

Figure 2 is a view in cross section of the lamp shown in Figure 1 of the drawings and taken in a plane represented by line 2—2 of Figure 4 of the drawings;

Figure 3 is a view in cross section through the device as shown in Figure 1 and taken in the plane represented by line 3—3 of Figure 4 of the drawings;

Figure 4 is a view in cross section taken in the plane represented by line 4—4 of Figure 3 of the drawings;

Figure 5 is a fragmentary view in cross section taken in the plane represented by line 5—5 of Figure 3 of the drawings;

Figure 6 is a view in perspective of a switch member used in this modified lamp assembly;

Figure 7 is a fragmentary view in side elevation of the lamp housing disclosing control means for the switch element;

Figure 8 is a view in side elevation of a portable lantern disclosing additional features of construction comprehended by the present invention;

Figure 9 is a view in end elevation of the portable lantern disclosed in Figure 8 of the drawings;

Figure 10 is a view in side elevation at substantially 90 degrees to that of Figure 8, disclosing in dotted lines an adjusted position for the said lantern with respect to the support therefor; and

Figure 11 is a fragmentary view in cross section of the lantern of Figures 8, 9 and 10, disclosing novel means for completely insulating the battery from the lantern housing.

In Figures 1 to 7 inclusive an embodiment selected to illustrate the present invention is shown as comprising a housing 50 having a detachable cover or cap 52 at one end and a reflector head 54 at the other end. The housing 50 is formed of two substantially U-shaped parts 56 and 58 connected together in overlapping relation as by means of rivets 60 which likewise secure a finishing channel strip 62 to the housing at the overlapped edges of parts 56 and 58. The housing 50 is closed at one end by the reflector head 54 which comprises a substantially circular-shaped plate 64 having an annular flange 66 which telescopically receives reflector 68 and secures the same in such position as by means of a plurality of bolts or screws 70. This reflector head 54 is secured in operative position at the said end of the housing 50 by means of the opposed brackets 72 and 74. Each of said brackets has one leg thereof secured to the plate member 64 by spot welding or the like, and the other leg thereof is received in one of the opposed recesses 76 of housing 50. The said brackets are secured to the housing by means of a plurality of rivets 78 which also extend through plates 82 disposed exteriorly of the housing 50 and have tubular upper end portions 84 through which the middle portions of the inverted resilient U-shaped wire elements 86 pass, the said wire elements being rigidly secured to the casing 50 through the said plates 82.

As already described, the other end of the housing 50 is normally closed by a detachable cover or cap 52 which is provided with a leaf spring 90 secured thereto by means of one or more rivets 92 and which spring is adapted to engage one end of a battery set 88 for resiliently holding the battery set within the housing and to prevent displacement thereof. This cover 52 is detachably connected to the housing 50 by means of oppositely disposed buttons 100 projecting through aligned openings in the housing and the marginal flange of the cover. These buttons 100 are secured adjacent one end of leaf springs 94 and 96 disposed adjacent the inner face of the housing and which springs, adjacent their other end, are connected to the said housing by means of rivets 98 or the like. Inasmuch as these buttons are resiliently mounted and project through the flange of the cover, the said cover may be easily and readily detached from the housing by pressing one or more of the said buttons to release their engagement with the cover and permitting removal thereof from the housing.

The plate member 64 of the reflector head is formed with an elongated slot 104 through which projects a spring contact element 106 secured by means of a rivet 110 to an insulating plate 108. Rivet 110 likewise secures a contact plate 112 to the said insulation plate 108, which contact plate is adapted to be engaged by a spring terminal 114 of the said battery set 88. This plate 112 is disposed in concentric relation with respect to the marginal edge of an opening formed in a plate 116 which is offset to receive the insulating plate 108 and is provided with flanges 118 and 120 which may be secured to the plate 64 by spot welding or the like, whereby the insulating plate and contact plate 112, as well as the spring contact 106, are held in operative position, such position being further maintained by

way of a plurality of rivets such as 122 which extend through plates 116, 108 and 64. These rivets also establish an electrical circuit to the reflector head through plate 66 and plate 116 which is engaged by a leaf spring terminal 124 of the battery set.

The reflector 68 is formed with a concave or dished surface 126 adjacent the bottom of which is provided a channel 128 having an elongated slot 130 provided therein, this channel 128 being adapted to seat a movable switch 132 which is formed with side walls 134 and 136 connected together by a connecting wall or web 138. This switch is slidably mounted within the channel 128 and is maintained in position by means of leaf springs 140 and 142 secured in offset relation to plate 64 by means of rivets 144 and serving as guide rails adapted to engage the side walls 134 and 136 of the said switch.

This switch further provides a mounting for a plurality of lamps such as 146 and 148, each of which is mounted within a socket, such as 150, which extends through a suitable aperture in the connecting web 138 of the switch and is held in position by a nut 152 threadedly engaging the same, the said nut 152 having an insulating sleeve 154 mounted within a central opening formed therein and which is secured thereto by way of a rivet 156, one end of which within the socket 150 is adapted to engage the end of a lamp, and the other end of which provides a contact engageable with the spring contact 106. Rivet 156 at its inner end is insulated from nut 152 by way of the insulating plate 153 which bridges the two nuts 152, the said rivet having a washer 160 interposed between its inner head and the said insulating plate 153.

It will therefore be clearly apparent that the switch 132 is adapted to complete a circuit from the battery set through either one of the lamps 146 or 148 and also provides a mounting for said lamps to dispose the same exteriorly of the reflector head at all times whereby either one of said lamps may be moved to establish an electrical circuit thereto for signaling purposes or the like.

The movement of switch 132 is effected by way of a switch member 162 disposed on one side of plate 64 and fixed to a pin 164 pivoted in plate 64 and to which is fixed an operating member 166 in the form of a plate disposed within recess or depression 168 on the other side of plate 64, the said operating member 166 having a knob, such as 170, for operation of the said switch 132 through plate 166 and pivot pin 164.

The switch element is made of phosphor-bronze or other suitable material of the shape disclosed in Figure 4 of the drawings, to include the spaced arms 172 and 174 bridged adjacent the ends thereof by a head 176 formed with an aperture 178 and a projecting operating finger 180 adapted to be received between and in engaging relation to spaced abutments 182 and 184 formed as struck-out portions of wall 133 of switch 132. It will therefore be clearly apparent that movement of the knob 170 moves switch 132 through the interconnection of switch element 162 and abutments 182 and 184.

In order to position the switch member 162, a protuberance or button 186 may be provided in opposed relation to aperture 178 when switch member 162 is in its central position and which protuberance is likewise adapted to engage the said switch member at the junction of the arms 172 and 174 with head 176 when the switch has

been moved to complete a circuit through either of the lamps 146 or 148. In this connection it should be noted that the button 166 projects a sufficient distance from the face of plate 64 to flex member 162 upon operation so that the spring tension of member 162 will hold the same in association with button 166 in any of its operative positions. If desired, button 166 may constitute a part of securing means for securing spring rail 142 to plate 64, as shown in the drawings.

As an additional feature of construction incorporated to facilitate proper operation of the switch and to control the movement thereof, novel means is provided adapted to cooperate with the switch operating member 166 and knob 170 to control the operation thereof. Such means is constituted by a spring plate 188 formed with a central part 171 and angularly disposed end parts 173 and 175 having ears 190 and 192, respectively, adapted to embrace the underside of plate 64 and to provide stops for the said switch operating element 166. This spring plate is formed with a slot in the central part 171 having enlarged end parts 194 and 196 interconnected by way of the restricted part 198, the said slot embracing a stud pin 200 secured to and projecting from the reflector head at the annular flange 66 adjacent the knob 170 of switch operating element 166. This pin is headed as at 202 adapted to overlap the marginal edges of the slot of spring element 188 for maintaining the same in position and restricting the same to movement in the direction of the said slot thereof. The said pin 200 adjacent the head 202 is formed with an enlarged cylindrical part 206 of slightly less diameter than the width of slot openings 194 and 196, and a cylindrical part 208 inwardly thereof of slightly less diameter than the cylindrical part 206 and of slightly less width than the restricted slot portion 198.

Because of the angular relation of the parts 173 and 175 with respect to the central part 171, the said member 188 is normally disposed, because of its resiliency, in abutting engagement with the head 202, the said plate 188 being restricted in its movement because of the enlarged cylindrical part 208 which is adapted to be received in either of the enlarged slots 194 or 196 but which is prevented from movement by way of the restricted slot 198. However, when it is desired to move the member 188, the same may be pressed slightly toward the flange 66 to disengage the cylindrical part 206 from either of the two slot parts 194 or 196 whereby the restricted slot 198 is in opposed relation to the cylindrical part 208. Movement of the member 188 with respect to annular flange 66 may take place at this time, so as to change the relative positions of the ears 188 and 190 with respect to the switch operating element 166. The particular formation of the spring plate including the angular disposition of parts 173 and 175 with respect to the central part 171 facilitates release of said member 188 from engaging relation with the pin and its movement with respect thereto.

The ears 190 and 192 serve as abutments to control movement of switch element 166 and knob 170, it being noted that when the said member 188 is in one of its positions switch element 166 can be operated to move between its central position and one of its extreme angular positions for moving one of the lamps into and out of the electrical circuit described herein-

above. On the other hand, if member 188 is moved into its other position, movement of switch element 166 is limited between its normal central position and its other extreme angular position whereby only the other lamp can be moved into and out of the circuit as hereinbefore described. This novel control means therefore facilitates proper operation of the lantern under all normal conditions, and should one of the lamps become broken or burned out, it is only necessary to move the member 188 into the other of its positions whereby the other of the lamps may be moved into and out of its electrical circuit.

15 The U-shaped wire elements 86 extending beyond the lamp housing are connected to a ring 210 which serves as a means for supporting the lamp when not in use and as a guard to prevent injury or breakage to the lamps 146 or 148 or 20 other associated elements of the device.

The present invention also embraces within its scope novel means providing a support for the portable lantern, one embodiment selected to disclose this feature of the construction being 25 shown in Figures 9 to 11 inclusive wherein the portable lantern is provided with a housing 210 including a reflector head 212 and a removable end cap 214 adapted to enclose a battery 216, all as hereinbefore described in connection with 30 Figures 1 to 7 inclusive. The said lantern may embrace the structure shown in the said figures, providing means for completing a circuit from the battery to one of a plurality of lamps by way of the switch operating member 218 and associated elements controlled as by means of the mechanism 220, all in accordance with the previously described lamp structure. In the present embodiment the lamps are protected by a globe 222 secured to the reflector head by way of a plurality of clips 224 embracing the annular flange of the globe 222 and being secured by 35 means of bolts or screws 226 which may be apertured as at 228 to receive a sealing device which may be used under certain conditions to prevent removal of the said globe and the lamps enclosed thereby and mounted within the reflector head. In order to facilitate drawing of the clamps 224 into position without breaking the said globe 222 and to provide a tight joint 40 between the globe 222 and the reflector head 212, a gasket 213 may be interposed between the globe and reflector head.

As in the previously described embodiment, the 45 lamp guard comprises opposed U-shaped wire elements 230 secured within the tubular rolled edges 232 of bracket elements 234 attached to the housing 210 and fixedly securing the said elements in projected relation to the reflector head. The lamp guard is completed by means of a wire ring 236 connected adjacent the ends of wire elements 230, all as disclosed in Figures 1 to 7 inclusive. The portable lantern of the embodiment now being discussed is provided with laterally projecting pins such as 238 providing pivots for a handle 240 which is held in place by nuts 242 secured to the said pins. These pins may likewise provide pivot points for a support 244 which is formed in part by the side plate members 246 and 248 pivoted to the pins 238, a plurality of washers 250 of any suitable material being interposed between the elements at the pivot to provide frictional resistance for holding the housing 210 in any of its angularly adjusted positions with 50 respect to the support 244. These side plates

246 and 248 are formed with marginal rolled edges 252 adapted to embrace U-shaped wire elements 254 laterally disposed in respect to the lamp guard previously described and having attached at their ends a wire ring 256, which wire ring, in conjunction with the elements previously described, provides a support whereby the lamp housing may be pivoted into a plurality of angular positions with respect to the base about the pivot points 238 as shown in dotted lines in Figure 10 of the drawings. The said support 244 is constructed and arranged with respect to the previously described lamp guard so as to provide clearance therewith whereby the lantern can be moved into angular relation with the support, the said support also being disposed in such a position as to have the additional function of protecting the reflector head and associated mechanism, as well as the lamp guard, from injury.

As an additional feature of construction, provision has been made to guard against possible short-circuiting of the battery set which might otherwise occur under certain conditions where the battery set is inserted into the lantern housing 210 in a position reversed from that which it normally assumes for cooperative relation with the various elements of the reflector head. In order to prevent such short-circuiting with resultant dissipation of electrical energy, the removable closure member 214 is provided with an insulating plate 258 secured thereto in association with the leaf spring 264 and by the rivets 262 by which the leaf spring 264 is attached to the closure member. This insulating plate 258 is disposed to be engaged by the spring terminal 269 of the battery 216 should the same be placed within the housing 210 in the reverse position as shown in Figure 11. This plate 258 of insulating material prevents the completion of a circuit from the spring terminal 260 through the housing to the other terminal for the battery set, thereby preventing short-circuiting of the said battery set when the battery set is placed within the housing in a reverse position from that which it normally assumes to cooperate with the various elements of the reflector head. Accordingly, it may be stated that the providing of insulating material 258 as disclosed results in a lamp structure wherein the battery is completely insulated at all times to prevent short-circuiting irrespective of its position within the housing, a circuit being completed therethrough only as desired by proper manipulation of the switch at the reflector head controlling the circuit to one or more of the lamps which may be provided in said head. The structure is therefore "fool-proof" and guards against the dissipation of electrical energy from the battery even though the said battery is inadvertently placed within the housing in a reverse position from that which it normally assumes.

In order to completely seal the lantern and to prevent removal of any of the elements thereof, apertured pins, such as 266, may be provided on opposite sides of the housing 210 and adjacent the removable closure element 214 to receive the wire element of sealing mechanism which is adapted to extend over the closure element 214 to prevent removal thereof from the housing 210, thus providing a structure which cannot be readily tampered with, a particularly desirable characteristic where lanterns of the type herein described are used in the vicinity of gas wells, gasoline and the like.

While I have herein described and upon the drawings shown illustrative embodiments of the

invention, it is to be understood that the invention is not limited thereto but may comprehend other constructions, arrangements of parts, details and features without departing from the spirit of the invention.

I claim:

1. In an electrical lantern, the combination of a housing, a source of electrical energy, a lamp, means associated with said housing for establishing an electrical circuit from said source of electrical energy through said lamp, said means including a switch mounted adjacent one end of said housing for linear movement transversely with respect to said housing, means for mounting said lamp for movement in accordance with the movement of said switch, and means pivotally mounted in said housing and operable exteriorly thereof and articulately connected with said switch for operation of the same and for moving said lamp into and out of said circuit.

2. In an electrical lantern, the combination of a housing, a source of electrical energy, a lamp, means for movably mounting said lamp with respect to said housing, means associated with said housing for establishing an electrical circuit from said source of electrical energy through said lamp, said means including a switch mounted adjacent one end of said housing for linear movement transversely with respect to said housing and for moving said lamp with respect to said housing into and out of said circuit, and means pivotally mounted in said housing and operable exteriorly thereof and articulately connected with said switch for simultaneously operating said switch and moving said lamp.

3. In an electrical lantern, the combination of a housing having a reflector head, a source of electrical energy, a plurality of lamps, means associated with said housing for establishing an electrical circuit from said source of electrical energy through any one of said lamps, said means including a switch mounted in said reflector head for transverse linear movement with respect thereto and having means for mounting said lamps for positioning the same exteriorly of said reflector head, and pivotally mounted means operable exteriorly of said housing for operating said switch to position any one of said lamps substantially centrally with respect to said reflector head and to complete a circuit from said source of electrical energy therethrough.

4. In an electrical lantern, the combination of a housing including an outer wall, an opposed inner wall, a source of electrical energy, contact means in electrical association with said electrical energy, a switch member mounted for sliding movement in cooperative relation with and disposed between said walls, said switch member having contact means engageable with said first-named contact means to complete and interrupt an electrical circuit established through said switch from said source of energy, said switch member comprising a substantially U-shaped member having side walls and a connecting web, spaced abutments provided on one of said side walls, and a pivoted switch member having a part normally disposed between said abutments for operation of said first-named switch member.

5. In an electrical lantern, the combination of a housing including an outer wall, an opposed inner wall, a source of electrical energy, contact means in electrical association with said electrical energy, a switch member mounted for sliding movement in cooperative relation with and

disposed between said walls, said switch member having contact means engageable with said first-named contact means to complete and interrupt an electrical circuit established through said switch from said source of energy, said switch member comprising a substantially U-shaped member having side walls and a connecting web, means connected to said connecting web providing a lamp mounting, spaced abutments provided on one of said side walls, and a pivoted switch member having a part normally disposed between said abutments for operation of said first-named switch member.

6. In an electrical lantern, the combination of a housing including a reflector provided with a channel, an opposed wall, a source of electrical energy, contact means in electrical association with said electrical energy, a switch member mounted for sliding movement in said channel, said switch member having contact means engageable with said first-named contact means to complete and interrupt an electrical circuit established through said switch from said source of energy, resilient means on said wall cooperating with said switch member for positioning the same within said channel, said switch member comprising a substantially U-shaped member having side walls and a connecting web, means connected to said connecting web providing a lamp mounting, one of said walls having parts struck out therefrom to provide spaced abutments, and a pivoted switch member having a part normally disposed between said abutments for operation of said first-named switch member.

7. An electrical lantern, comprising a housing having a slot adjacent one end thereof, a source of electrical energy, means associated with said housing for establishing an electrical circuit with said source of electrical energy including electrical contact means, a linearly movable switch member having electrical contact means adapted to engage said first-named electrical contact means, a plurality of lamps mounted in said switch member and extending through said slot and being disposed exteriorly of said housing, said switch member having means for selectively introducing said lamps into said circuit, and an actuating device pivotally mounted upon and operable exteriorly of said housing and separably and articulatedly associated with said switch member for selectively moving the same.

8. An electrical lantern, comprising a housing having a slot adjacent one end thereof, a source of electrical energy, means associated with said housing for establishing an electrical circuit with said source of electrical energy including electrical contact means, said housing having opposed walls adjacent one end thereof, a linearly movable switch member having electrical contact means adapted to engage said first-named electrical contact means slidably mounted between said opposed walls, a plurality of lamps mounted in said switch member and extending through said slot and being disposed exteriorly of said housing, said switch member having means for selectively introducing said lamps into said circuit, and an actuating device pivotally mounted upon and operable exteriorly of said housing and separably and articulatedly associated with said switch member for selectively moving the same.

9. An electrical lantern, comprising a housing having a slot adjacent one end thereof, a source of electrical energy, means associated with said housing for establishing an electrical circuit with said source of electrical energy including elec-

trical contact means, a linearly movable switch member having electrical contact means adapted to engage said first-named electrical contact means, a plurality of lamps mounted in said switch member and extending through said slot and being disposed exteriorly of said housing, said switch member having means for selectively introducing said lamps into said circuit, an actuating device pivotally mounted upon and operable exteriorly of said housing and separably and articulatedly associated with said switch member for selectively moving the same, and means for selectively controlling the operation of said last named device.

10. In an electrical lantern, the combination of a housing having a transversely disposed wall of concave formation adjacent one end thereof provided with a channel-shaped recess projecting into the concave transversely disposed wall and having a slot through the bottom wall thereof, a source of electrical energy, means for establishing an electrical circuit with said source of electrical energy including a movable switch member mounted in and having sliding association with the walls of said recess, and a lamp mounted in said switch member movably disposed in said slot.

11. In an electrical lantern, the combination of a housing having a transversely disposed wall of concave formation adjacent one end thereof provided with a channel-shaped recess projecting into the concave transversely disposed wall and having a slot through the bottom wall thereof, a source of electrical energy, means for establishing an electrical circuit with said source of electrical energy including a movable switch member mounted in and having sliding association with the walls of said recess, resilient means for positioning said switch within said channel, and a lamp mounted in said switch member movably disposed in said slot.

12. In an electrical lantern, the combination of a housing having a transversely disposed wall of concave formation adjacent one end thereof provided with a channel-shaped recess projecting into the concave transversely disposed wall and having a slot through the bottom wall thereof, a source of electrical energy, means for establishing an electrical circuit with said source of electrical energy including a movable switch member mounted in and having sliding association with the walls of said recess, a lamp mounted in said switch member movably disposed in said slot, and a second switch member manually operable exteriorly of said housing and operatively connected to said first switch member.

13. An electrical lantern, comprising a housing, a source of electrical energy, means associated with said housing for establishing an electrical circuit with said source of electrical energy, a plurality of lamps adapted to be introduced into said circuit and mounted for movement exteriorly of said housing, a switch mounted adjacent one end of said housing for linear movement transversely with respect to said housing and being movable into a plurality of positions to complete and interrupt the said circuit for any selected lamp, a pivoted flexible switch member pivotally mounted in said housing and operable exteriorly thereof and operatively connected to said switch, and means positioned to flex said flexible member and cooperating therewith when flexed for maintaining said switch member in certain of its selected positions.

14. An electrical lantern, comprising a housing,

a source of electrical energy, means associated with said housing for establishing an electrical circuit with said source of electrical energy, a plurality of lamps adapted to be introduced into said circuit and mounted for movement exteriorly of said housing, a switch mounted adjacent one end of said housing for linear movement transversely with respect to said housing and being movable into a plurality of positions to complete and interrupt the said circuit for any selected lamp, a pivoted switch member pivotally mounted in said housing and operable exteriorly of said housing and operatively connected to said switch, and means cooperating with said switch member for selectively controlling the operation thereof.

15. In an electrical lantern, the combination of a housing including a reflector provided with a channel, an opposed wall, a source of electrical energy, contact means in electrical association with said electrical energy, a movable switch member mounted in said channel, said switch member having contact means engageable with said first-named contact means to complete and interrupt an electrical circuit established through said switch from said source of energy, spring means attached to said opposed wall and providing resilient rails for said switch member, said switch member having spaced abutments, a pivoted switch member extending exteriorly of said housing for manual operation, said pivoted switch member having a projection disposed between said abutments for operating said first-named switch member, and means cooperating with said pivoted switch member for selectively controlling operation thereof.

16. In an electrical lantern, the combination of a housing, a source of electrical energy, contact means in electrical association with said electrical energy, a switch member, means for mounting said switch member for movement within said housing, said switch member having contact means engageable with said first-named contact means to complete and interrupt an electrical circuit established through said switch from said source of energy, said switch member having spaced abutments, a pivoted switch member operable from exteriorly of said housing and including a flexible part having a projection disposed between said abutments for operation of said first-named switch member, a protuberance projecting slightly above the normal plane of operation of said flexible part, said part having means cooperating with said protuberance whereby said first-named switch member is held in any of its various positions, and a readily adjustable

control member exteriorly of said housing cooperating with said pivoted switch member for selectively limiting the movement of said first-named switch member between certain of its said various positions.

17. An electrical lantern, comprising a housing, a source of electrical energy, means associated with said housing for establishing an electrical circuit with said source of electrical energy, a plurality of lamps adapted to be introduced into said circuit and mounted for movement exteriorly of said housing, a switch movable into a plurality of positions to complete and interrupt the said circuit for any selected lamp, a pivoted flexible switch member operable exteriorly of said housing and operatively connected to said switch, and means interlocking with said flexible switch member for positioning the same in its selected positions, said means being positioned to cause flexing of said flexible member in moving into and out of its said positions to assure proper interlocking relation of said means and member.

18. In an electrical lantern, the combination of a housing, a source of electrical energy, means for establishing an electrical circuit with said source of electrical energy including a switch mounted within said housing for movement into a plurality of operating positions, a switch operating member having a part exteriorly of said housing and movable with respect thereto, and a control member selectively adjustable with respect to said part to provide for movement of said switch into said plurality of operating positions but selectively restricting the movement of said switch in any of its adjusted positions between certain only of said plurality of operating positions.

19. In an electrical lantern, the combination of a housing, a source of electrical energy, means for establishing an electrical circuit with said source of electrical energy including a switch movably mounted within said housing for movement into a plurality of operating positions, a switch operating member having a part exteriorly of said housing and movable with respect thereto, and a control member selectively and interlockingly adjustable with respect to said housing and having abutting means selectively movable into a plurality of positions to provide for movement of said switch into said plurality of operating positions but selectively restricting the movement of said switch in any of its adjusted positions between certain only of said plurality of operating positions.

CHARLES S. PACKER.
